United States Patent Office

Des. 179,753
Patented Feb. 26, 1957

179,753

DRESS

Florence Barrack, New York, N. Y.

Application September 20, 1956, Serial No. 43,011

Term of patent 3½ years

(Cl. D3—26)

Fig. 1.

Fig. 2.

I claim:

The ornamental design for a dress, substantially as shown.
